UNITED STATES PATENT OFFICE

GEORGE R. MOON, OF CLEVELAND, OHIO.

OVEN.

No. 888,108.

Specification of Letters Patent.

Patented May 19, 1908.

Application filed September 30, 1907. Serial No. 395,062.

To all whom it may concern:

Be it known that I, GEORGE R. MOON, citizen of the United States, residing at Cleveland, in the county of Cuyahoga and State of 5 Ohio, have invented certain new and useful Improvements in Ovens, of which the following is a specification.

My invention relates to ovens and has for its object the provision of a device of this 10 character constructed in such manner that the bottoms of the shelves upon which articles to be baked are placed, are protected from the direct action of the heat and said heat is caused to enter the compartments 15 from the top, by virtue of which construction the material to be baked is as thoroughly cooked around its edges as at the center.

Further objects and advantages of the invention will be set forth in the detailed description which now follows.

In the accompanying drawing: Figure 1 is a perspective view of an oven constructed in accordance with the invention, with the door of said oven broken away, Fig. 2 is a 25 transverse vertical section through said oven, Fig. 3 is a longitudinal vertical section upon line $x-x$ of Fig. 2, and Fig. 4 is a detail horizontal section through one corner of the oven.

Like numerals designate corresponding 30 parts in all of the figures of the drawing.

Referring to the drawing, the numerals 5 designate the side walls of the oven, the numeral 6 designates the top wall, the numeral 7 designates the rear wall and the 35 numerals 8 designate strips of metal located at the front of the oven and forming substantially door jambs. A door 9 is hinged to one of these strips as at 10 and is adapted to close the front of the oven.

40 A compartment 11 is formed at the upper part of the oven by a plate 12, this plate having a row of centrally located holes 13 formed therein extending from the front of the oven to the rear thereof. A flue collar 14 adapted 45 to have a flue slipped thereupon, leads from the compartment 11. A lower shelf 15 and an upper shelf 16 are provided with upwardly extending side walls 17. These side walls extend from the door jambs 8 to the rear wall 50 of the oven. The side walls 17 and the baffle plates 21 are formed in one piece and these side walls are riveted at each end to angle plates 30. These angle plates carry lugs 31 which support the shelves 16. When these 55 shelves are placed in position and forced downwardly, the side walls and the angle plates 30

to which the side walls are riveted, are spread apart and bound against the sides of the oven. It will therefore be seen that the angle plates, the shelves, the side walls of the 60 shelves, and the baffle plates are held in position without being riveted to the walls of the oven. A V-shaped spreader 22 is secured to the bottom of the shelf 15 and protects said shelf against the direct action of heat 65 from a gas burner 23, said burner being of any desired construction, but extending substantially the full length of the oven.

The operation of the device is as follows: When gas from the burner is ignited, the heat 70 products from said burner travel up the sides of the oven, some of the heat being directed by the baffle plates 21 over the side walls of the shelf 15 and some of the heat passing upwardly and being directed by the baffle 75 plates 20 over the side-walls of the upper shelf 16 and into the upper and lower compartments of the oven. The material to be baked, it will therefore be seen, is effectually protected against the direct action of heat 80 from the burner 23. Where walls such as 17 are not provided, the heat passes directly over the edges of the shelves and strikes first against the edges of the material that is being baked and burns this material around its 85 edges, before the center is thoroughly cooked. These side walls protect the material being baked against such action as this and the baffle plates direct the heat over toward the center of the compartments, the result being 90 that the material is as thoroughly cooked at its center as at its edges. No heat can escape from the oven except through the centrally located openings 13. The heat must travel to the center of the oven above the upper compartment, therefore, before it can escape. It passes through the openings 13 to the compartment 11 and thence to the flue.

95 From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

100 What I claim, is:

110 1. An oven comprising an outer shell, an upper shelf and a lower shelf located cen-

trally within said oven, side walls carried by
said shelves upon each side thereof, said side
walls being spaced from the side walls of the
oven, a flame spreader located beneath the
5 lowermost shelf, a burner located beneath
said flame spreader, a baffle plate located at
each side of the upper shelf and directed di-
agonally downward to direct heat from the
burner inwardly over the side walls of the
10 lower shelf, a compartment located at the
top of the oven, baffle plates located at each
side of the oven and arranged to direct heat
from the burner inwardly over the upper
edges of the side walls of the upper shelf,
15 there being a centrally located means of com-
munication between the oven and the upper
compartment and a flue leading from the up-
per compartment.

2. An oven comprising an outer shell, an
upper shelf and a lower shelf located cen-
trally within said oven, side walls carried by
said shelves upon each side thereof, said side
walls being spaced from the side walls of the
oven, a flame spreader located beneath the

lowermost shelf, a burner located beneath 25
said flame spreader, a baffle plate located at
each side of the upper shelf and directed di-
agonally downward to direct heat from the
burner inwardly over the side walls of the
lower shelf, a compartment located at the 30
top of the oven, baffle plates located at each
side of the oven and arranged to direct heat
from the burner inwardly over the upper
edges of the side walls of the upper shelf,
there being a centrally located means of com- 35
munication between the oven and the upper
compartment and a flue leading from the up-
per compartment, vertically extending angle
plates to which the side walls are secured and
lugs carried by said vertically extending an- 40
gle plates adapted to support the shelves.

In testimony whereof I affix my signature
in presence of two witnesses.

GEORGE R. MOON.
